DESIGN FOR A GLOVE OR SIMILAR ARTICLE

Isabel Ireland, New York, N. Y.

Application December 19, 1938, Serial No. 81,869

Term of patent 3½ years

To all whom it may concern:

Be it known that I, Isabel Ireland, a citizen of the United States, residing in the city of New York, county of New York, and State of New York, have invented a new, original, and ornamental Design for a Glove or Similar Article, of which the following is a specification, reference being had to the accompanying drawing, forming a part thereof.

The characteristic feature of the design resides in three checkered rows around the body portion of the glove in combination with initials on the back thereof in staggered relation, as shown.

I claim:

The ornamental design for a glove or similar article, as shown and described.

ISABEL IRELAND.
